UNITED STATES PATENT OFFICE.

BENJAMIN T. FERGUSON AND RICHARD F. FENTON, OF STANDARD, LOUISIANA.

SPARKING PLUG.

1,103,187.

Specification of Letters Patent. Patented July 14, 1914.

Application filed July 10, 1912. Serial No. 708,717.

To all whom it may concern:

Be it known that we, BENJAMIN T. FERGUSON and RICHARD F. FENTON, citizens of the United States, residing at Standard, in the parish of La Salle and State of Louisiana, have invented certain new and useful Improvements in Sparking Plugs, of which the following is a specification, reference being had to the accompanying drawings.

10 This invention relates to new and useful improvements in sparking plugs used primarily in internal combustion engines and is of a type wherein a succession of sparks are formed at the inner end of the plug to 15 make the ignition of the gases more certain to create explosions.

The primary object of the present invention is to provide a spark plug of the character aforesaid, with an electrode extending 20 diagonally through the core of insulation to coöperate with a plurality of electrodes or bridges mounted in the lower end of the core of insulation which will give a series of sparks without splitting the current, there- 25 by carrying the full current across each point to the ground.

With the above and other objects in view, this invention consists of the novel details of construction, formation and arrangement 30 of parts as will be hereinafter more fully described and the advantages will be herein- after referred to and particularly pointed out in the appended claim.

In the drawings, Figure 1 is a vertical section taken through the casing of our im- 35 proved sparking plug showing the core of insulation in elevation. Fig. 2 is a similar section taken at right angles thereto, and Fig. 3 is a bottom plan view of the same.

40 Reference now being had more particu- larly to the drawings wherein we have illus- trated corresponding parts by like numerals throughout the several views, this improved plug consists of a casing 1 of any preferred 45 pattern of construction and has formed at its inner end with threads 2 which are adapted to engage with threads formed in the opening within the cylinder for receiv- 50 ing the plug in the usual and well known manner. This casing is provided with a central bore in which is mounted the core of insulation made of porcelain, mica, or any other suitable insulation material indicated by the numeral 3. This core of insula- 55 tion is provided with an annular flange which is adapted to rest against a shoulder

4 formed within the casing. To provide means for holding the core of insulation within the bore formed in the casing, we provide a nut 5, having threads mounted on 60 the periphery thereof adapted to engage the threaded portion of the bore, in the usual and well known manner.

The conductor, indicated by the numeral 6 extends diagonally through the core of insulation from the center of the upper end to one side of the center at its lower end and then terminating in a hooked tip or bridge 7. Also mounted within the lower extremity of this core is a plurality of hooked 70 wires or bridges 8 which are held in spaced relation as shown. The said bridges having their hooked ends extending in opposite directions, but terminating in a line extending lineally across the center of the lower face 75 of the core. An electrode 9 is mounted within the lower extremity of the casing having a hooked end which is in alinement with the ends of the aforementioned elec- 80 trodes.

From the foregoing description, it is ap- 85 parent that a full current will be carried across each of the hooked ends of these bridges or electrodes without splitting the current thereby arranging a series in a cir- 90 circuit to form a succession of jump-sparks. The arrangement of these hooked ends will obviously make four jump-sparks in such close succession within the cylinder that it creates a sheet of flame extending substan- 95 tially entirely across the lower end face of the core which makes ignition more positive in that it ignites a greater volume of gas.

Wherein we have shown a specific em- bodiment of the present invention, it is of 95 course, to be understood that there may be as many of these bridges as desired, there- by increasing or diminishing the number of sparks and it is to be further understood that other minor details of construction may 100 be resorted to that come within the scope of the present invention without departing from the spirit thereof.

Having thus described our invention, what we claim is:

A spark plug comprising a casing, a core 105 of insulation therein, a ground electrode fixed to the lower end of the casing and hav- ing its terminal disposed at one side of the core and contiguous thereto, a plurality of 110 electrodes mounted in staggered relation in the lower end of the core and projecting

from the bottom face thereof, said electrodes being equally spaced from each other and having oppositely disposed hooked ends terminating upon a line extending diametrically across the bottom face of the core and in alinement with the terminal of the ground electrode, whereby a line of sparks extending substantially entirely across the bottom face of the core is produced.

In testimony whereof we hereunto affix 10 our signatures in the presence of two witnesses.

BEN. T. FERGUSON.
RICHARD F. FENTON.
